UNITED STATES PATENT OFFICE.

CHARLES E. DURYEA, OF PEORIA, ILLINOIS.

DESIGN FOR A BICYCLE-FRAME.

SPECIFICATION forming part of Design No. 27,103, dated May 25, 1897.

Application filed January 6, 1896. Serial No. 574,551. Term of patent 7 years.

To all whom it may concern:

Be it known that I, CHARLES E. DURYEA, a citizen of the United States, residing at Peoria, in the county of Peoria and State of Illinois, have invented and produced a new and original Design for Bicycle-Frames, of which the following is a specification, reference being had to the accompanying drawing.

The figure is a side elevation view of the bicycle, and with the following description is deemed sufficient to fully illustrate the design of the frame.

The leading feature of my design consists in a bicycle-frame the members or tubes of which, as an entirety, present a triangular outline in side elevation. The triangular outline of the frame is defined by the front forks *a a'* and steering-post *A*, the rear brace-rod *B B*, and the horizontal reach-bars *C C*, as shown. The reach-bars *C C* constitute the base of the triangle, the sides being defined by the rear brace-tubes *B B* and the front

forks *a a'* and steering-tube *A*, these members forming a junction at the top of the frame and constituting the apex of said triangle. 25 The reach bars or tubes *C C* join the front or steering tube *A* at the top of the front forks *a a'*, the latter projecting forward of the triangle proper, but without materially detracting from the triangular outline or appearance 30 of the frame as a whole. The triangular outline is somewhat broken or departed from at the front part of the frame owing to the upward curvature of the reach-tubes *C C* at their front ends and the forward curvature 35 of the front forks *a a'*.

I claim—

The design for a bicycle-frame described and illustrated.

Witness my hand.

CHARLES E. DURYEA.
